MOLD-CARRIAGE.

1,083,996.

Specification of Letters Patent.

Patented Jan. 13, 1914.

Application filed March 25, 1913. Serial No. 756,689.

To all whom it may concern:

Be it known that I, HARRY H. DE LOSS, a citizen of the United States, residing at Bridgeport, county of Fairfield, State of Connecticut, have invented an Improvement 5 in Mold-Carriages, of which the following is a specification.

This invention has for its object to provide a carriage especially adapted for casting purposes, which will carry molds into position to receive molten metal from the pouring spout of a stationary furnace or from a tilting furnace and which shall be so constructed as to permit the molds to be reciprocated during the pouring operation, thereby dispensing with the labor and inconvenience of drawing or pouring the molten metal into a crucible and reciprocating the crucible during the operation of 20 pouring into the molds.

With these ends in view my invention consists in certain novel constructions, combinations and adjustments which will be hereinafter described and then specifically pointed out in the claims hereunto appended.

In the accompanying drawing forming a part of this specification, Figure 1 is an end elevation of my novel carriage as seen from the left in Figs. 3 and 4, parts being in section; Fig. 2 is a similar view showing a changed position of the parts, as in raising or lowering the upper ends of the molds; Fig. 3 a side elevation as seen from the right in Fig. 1, and Fig. 4 is a plan view.

So far as I am aware the operation of casting ingots is now performed by drawing or pouring the molten metal from the furnace into a crucible or other receptacle which must be lifted and held raised and reciprocated bodily over the top of the mold in order that the pouring may not be in one place in the mold. This is in order to prevent streaks, spills, air holes and other defects in the ingots, it having been found necessary in order to secure sound and solid ingots to deliver the stream of molten metal from end to end of the opening in the mold by moving the crucible or other pouring ves-

sel backward and forward over the top of the mold.

My present invention enables me to handle two molds at a time, to place them in convenient position to receive the metal from the furnace, to move the mold that is being filled backward and forward as the pouring 50 proceeds and when the mold is filled to move the other mold into position to be filled and to reciprocate the second mold in the same manner, all without any lifting whatever.

The invention furthermore does away 60 with intermediate handling of the molten metal and permits delivery of the metal from the furnace directly into the molds, thereby reducing the exposure of the molten metal to the atmosphere to the minimum and 65 greatly reducing the loss from oxidation of the metal.

My novel carriage as a whole comprises essentially a lower carriage 10 and an upper carriage 11. The lower carriage is of 70 greater width than length and consists simply of a relatively strong frame which may be constructed in any ordinary or preferred manner and is provided with wheels 12 upon which it is adapted to be moved backward 75 and forward and with transverse tracks or rails 13. The upper carriage is provided with flanged wheels 14 which are adapted to travel on the tracks, with a base 15, with a foot piece 16 and with a hinged support 17 80 upon which the upper ends of the molds rest, as indicated by dotted lines. This support is made high enough to provide for varying lengths of molds which are ordinarily supported at an incline, as indicated 85 by dotted lines. As a convenient rest for the bases of the molds I ordinarily use a block or blocks 18 which may be removable and which rest against the footpiece, the tops of the molds resting upon the hinged 90 support. The support is provided with a hinged locking arm 19 having notches 20 either of which is adapted to engage a pin 21 which projects from the base of the upper carriage. The upper ends of the molds 95 are raised or lowered as may be required in

pouring from different furnaces by swinging the support toward or from the vertical position, compare Figs. 1 and 2.

22 denotes an oscillating bar, one end of which is pivoted to the upper carriage as at 23, the other end being provided with notches 24 either of which is adapted to engage a pin 25 which projects from an oscillating lever 26, the lower end of which is 10 pivoted to a suitable bracket 27 projecting from the frame of the lower carriage.

The operation is as follows: The lower carriage with the upper carriage and molds thereon is run up to the furnace in position 15 to receive molten metal therefrom. The height of the upper end of the molds is adjusted to correspond with the furnace spout by means of the hinged support. If adjustment of the upper carriage is required 20 to place either mold in receptive position, for example the right mold as seen in Fig. 3, this adjustment is effected by disengaging the oscillating bar from the pin on the operating lever and moving the carriage 25 forward or backward on the tracks, as may be required. The furnace is then tapped and molten metal flows directly into the mold. During this pouring operation the upper carriage is oscillated forward and backward by means of the oscillating lever. This is in order that the 30 molten metal may be caused to enter the mold in a stream which is constantly moving from one end to the other of the opening in the mold, thereby avoiding streaks, spills, so-called, and air holes in the ingot. The difference between casting by the use of 35 my novel carriage and ordinary casting is that my novel carriage provides for oscillating the molds in a simple and convenient manner, whereas in ordinary casting the metal must be drawn off into a crucible or other receptacle and the receptacle must be held in a raised position by main strength 40 and moved bodily backward and forward over the upper ends of the molds. Having poured the first ingot the flow of metal is stopped, the oscillating bar is disengaged from the pin and the upper carriage is 45 moved into position to place the second mold in receptive position and then the operation of casting an ingot is proceeded with as before. Having cast ingots in the molds upon 50 the carriage, the carriage may be removed 55 from proximity to the furnace and the molds removed to permit the ingots to cool and other molds placed upon the carriage which is then run into position for another casting operation as before.

60 Having thus described my invention I claim:

1. A mold carriage comprising a lower carriage, an upper carriage adapted to

support a plurality of molds and to be moved transversely on the lower carriage 65 and means on the upper carriage for adjusting the height of the upper ends of the molds.

2. A mold carriage comprising a lower carriage, an upper carriage adapted to support a plurality of molds and to be moved transversely on the lower carriage, the upper carriage being provided with a hinged support upon which the upper ends of the molds are adapted to rest, and means for 75 adjusting said support to regulate the height of the upper ends of the molds.

3. A mold carriage comprising a lower carriage, an upper carriage adapted to support a plurality of molds and to be moved 80 transversely on the lower carriage, the upper carriage being provided with a hinged support on which the upper ends of the molds are adapted to rest and the base of the carriage being provided with a pin, and a locking arm pivoted to the support and provided with notches either of which is 85 adapted to engage the pin.

4. A mold carriage comprising a lower carriage, an upper carriage adapted to be 90 moved transversely thereon, an oscillating bar pivoted to the upper carriage and an oscillating lever pivoted to the lower carriage with which the oscillating bar is adjustably connected, whereby the upper carriage 95 may be oscillated during a pouring operation.

5. A mold carriage comprising a lower carriage, an upper carriage adapted to be moved transversely thereon, an oscillating 100 bar pivoted to the upper carriage and provided with notches, and an oscillating lever pivoted to the lower carriage and having a pin adapted to engage either of the notches, whereby the upper carriage may be oscillated 105 during a pouring operation.

6. A mold carriage comprising a lower carriage, an upper carriage adapted to be moved transversely thereon, a hinged support on the upper carriage, means for adjusting said support, for the purpose set forth, an oscillating bar pivoted to the upper carriage, an oscillating lever pivoted to the lower carriage and means for adjustably connecting the bar and the lever, for 115 the purpose set forth.

7. A mold carriage comprising a lower carriage having transverse tracks, an upper carriage adapted to travel on said tracks and means for oscillating the upper carriage on the tracks during a pouring operation.

8. A mold carriage comprising a lower carriage having transverse tracks, an upper carriage adapted to travel on said tracks, a 120 hinged support on the upper carriage for 125

the upper ends of molds and means for adjusting said support.

9. A mold carriage comprising a lower carriage having transverse tracks, an upper carriage adapted to travel on said tracks, a hinged support on the upper carriage for the upper ends of molds, means for adjusting said support and means for oscillating

the upper carriage on the tracks during a pouring operation.

In testimony whereof I affix my signature in presence of two witnesses.

HARRY H. DE LOSS.
